(57) **CLAIM**

The ornamental design for a housing connector, as shown and described.

DESCRIPTION

3.1 is a bottom view of the housing connector that we consider to be our invention;

3.2 is a front elevation view thereof;

3.3 is a left side view thereof;

3.4 is a right side view thereof;

3.5 is a rear elevation view thereof;

3.6 is a top view thereof; and

3.7 is a perspective view thereof.

In the reproductions, the broken lines are for the purpose of illustrating portions of the connector housing that forms no part of the claimed design.
